J. S. SELLON

UNITED STATES PATENT OFFICE.

JOHN S. SELLON, OF HATTON GARDEN, COUNTY OF MIDDLESEX, ENGLAND,
ASSIGNOR TO THE ELECTRICAL ACCUMULATOR COMPANY, OF NEW YORK.

SECONDARY BATTERY.

SPECIFICATION forming part of Letters Patent No. 396,958, dated January 29, 1889.

Application filed April 26, 1887. Serial No. 236,208. (No model.) Patented in England September 15, 1881, No. 3,987; in India August 22, 1882, No. 863; in Argentine Republic November 21, 1882, No. 354; in British Guiana December 11, 1882, No. 197/3,155; in Mexico January 27, 1883; in Canada March 15, 1883, No. 16,499; in Straits Settlements April 26, 1883, No. 25; in Chili June 8, 1883; in Brazil June 15, 1883, No. 53, and in Ceylon June 21, 1883.

To all whom it may concern:

Be it known that I, JOHN SCUDAMORE SELLON, a subject of the Queen of Great Britain and Ireland, resident at Hatton Garden, in the county of Middlesex, England, have invented certain new and useful Improvements in Secondary Batteries, (for which I have obtained a patent in Great Britain, No. 3,987, dated September 15, 1881; India, No. 863, dated August 22, 1882; Ceylon, dated June 21, 1883; Straits Settlements, No. 25, dated April 26, 1883; Argentine Republic, No. 354, dated November 21, 1882; British Guiana, No. 197/3,155, dated December 11, 1882; Mexico, January 27, 1883; Canada, No. 16,499, dated March 15, 1883; Chili, June 8, 1883, and Brazil, No. 53, dated June 16, 1883,) of which the following is a specification.

My invention relates to improvements in the construction and arrangement of batteries, known as "secondary batteries," used for the purpose of storing electricity.

My object is to provide a plate or support which will be less subject to oxidation, and which may be made lighter, while possessing greater rigidity or resistance to the contortion likely to be encountered in the process of formation or charging.

The improvements consist in the employment of plates or elements composed of two or more metals, of which lead and antimony are essential parts, and either made to adhere by mechanical pressure or other equivalent means or by the employment of metallic plates consisting of alloys of lead and antimony either with or without the use and application of an amalgam.

The form of plate or element preferred is one having grooves, perforations, or receptacles, in or upon which the active material or material to be rendered active is placed. Several appropriate forms are shown in my English patent, No. 3,987, September 15, 1881, and my United States patent, No. 259,657, June 13, 1882.

The accompanying drawings illustrate the preferred forms.

Figure 1 is a perforated plate having folds

or corrugations in which the active material is placed. Fig. 2 is a variation comprising substantially the same features. Fig. 3 shows a modification in which the strips are strung upon vertical rods in a frame. Fig. 4 shows an element composed of a number of perforated tubes of any suitable section supported in a frame.

In the process of manufacture I prefer that lead and antimony be mingled in a state of fusion. From five to twenty-five per cent. of antimony gives good results; but even a lower proportion of antimony may be successfully employed. A small amount of amalgam added to this alloy materially aids the union, and by its presence contributes somewhat to the beneficial result.

In the form shown at Figs. 1 and 2 the alloy plate *c* is provided with perforations *p* and folds forming cells, in and upon which the finely-divided active material—as a lead oxide or finely-divided lead, *a*—is applied.

In Fig. 3 there are perforated strips of the lead alloy, *S*, connected together to form a frame supporting strips *s* of the same material. To render this structure still more rigid, vertical rods *r* are passed through the strips.

In Fig. 4 there is a frame, *F*, containing perforated tubes *t* of the described alloy, in and upon which the active material is placed.

Connections for electrically uniting one cell with another consist of straps formed integral with and of the same material as the plate or support. I consider that a sheet of antimony and a sheet of lead united by pressure or equivalent means to be within the scope of my invention.

Two or more plates consisting of the described metals and combined with oxide of lead, which may be applied in the form of a paste, are placed in an electrolytic liquid and charged by subjecting them to the action of an electric current in the usual manner.

I do not herein claim in a secondary battery one or more plates, elements, or supports composed of or containing two or more metals and an amalgam thereof, nor in a secondary battery an element composed of a plate or sup-

port containing an alloy of two or more metals with an amalgam thereof in combination with an active material, nor do I herein claim the combination of an element composed of lead, 5 antimony, and an amalgam combined with an active material, as that forms the subject-matter of a divisional application filed by me in the United States Patent Office June 27, 1888, Serial No. 278,314.

10 What I claim, and desire to secure by Letters Patent, is—

15 1. In a secondary battery, the combination of a positive element containing lead and antimony combined with an oxide of lead, and a negative element containing lead and antimony combined with an oxide of lead, substantially as described.

2. In a secondary battery, a plate, element, or support containing lead and antimony, in combination with an active material. 20

3. In a secondary battery, a perforated plate, element, or support composed of lead and antimony, to, in, or upon which is applied an active material.

25 In testimony whereof I have signed my name to this specification in the presence of two subscribing witnesses.

JOHN S. SELLON.
